UNITED STATES PATENT OFFICE

123,429

DESIGN FOR A DECK OF CARDS

Leonard L. Dickman, Los Angeles, Calif.

Application March 4, 1940, Serial No. 90,647

Term of patent 14 years

To all whom it may concern:

Be it known that I, Leonard L. Dickman, a citizen of the United States, residing at Los Angeles, in the county of Los Angeles and State of California, have invented a new, original, and ornamental Design for a Deck of Cards, of which the following is a specification, reference being had to the accompanying drawings, forming part thereof.

Figs. 1 to 4 inclusive are face views of the cards of the deck showing my new design.

The backs of the cards are conventional.

I claim:

The ornamental design for a deck of cards, as shown and described.

LEONARD L. DICKMAN.
